UNITED STATES PATENT OFFICE.

FERDINAND W. KROGH, OF SAN FRANCISCO, CALIFORNIA.

DEEP-WELL PUMP.

1,169,266.

Specification of Letters Patent. Patented Jan. 25, 1916.

Application filed March 14, 1912. Serial No. 683,674.

To all whom it may concern:

Be it known that I, FERDINAND W. KROGH, of San Francisco, California, have invented certain new and useful Improvements in 5 Deep-Well Pumps, whereof the following is a specification.

My invention relates to centrifugal pumps in general way but more particularly of that class employed in deep wells where water is 10 below the suction limit and are usually constructed in plurality of sections or stages having an impeller in each section. I shall refer hereinafter for the purpose of this application to these sections singly, as they 15 are identical in form and construction and operate in the same manner, in which my invention consists mainly in the construction of the casing and the impeller operating therein.

It further consists of means on the impeller and its casing for balancing the running part thereof while in operation.

To carry out my invention in practice, I provide a pump casing with side spiral 25 passages and form therein removable diffusion vanes and in which an impeller mounted upon a central shaft operate. To the lower part of the casing I provide a removable bottom for the purpose of setting or adjusting the impeller therein or to remove the same therefrom when desired and provide centrally thereon an aperture which forms the suction inlet. At the lower end of the impeller I provide water ways in communication with the suction inlet and the spiral 35 passages just mentioned and at its upper end I provide a chamber adapted to receive leakages from the running joints and upon the interior part of the casing I provide an auxiliary chamber which is in constant communication with the receiving chamber and provide the same with outlet channel formed through the casing and the vanes, and communicating with the exterior part thereof. 40 At the upper part of the impeller I provide an annular flange projecting inwardly from its outer wall upon which I make a plurality of interspaced depressions forming thereby a series of surrounding ribs in communication with opposite similar flange upon the casing which receive leakage from the running joints at that point and con-

stitute a pressure space between the flanges. To the bearing faces of the running joints between the impeller and the casing I provide rifles or grooves spirally formed inwardly on the casing and outwardly on the impeller or vice-versa, respectively in opposite direction and are intended to check the leakage and force the water backward. I also provide other coöperating means to successfully operate my invention all of which will be hereinafter described in detail and the novel combinations of the various parts which compose the same will be pointed out in the claims at the end hereof.

The object of my invention is to simplify the construction of that class of inventions and increase their efficiency in operation.

In the accompanying drawings consisting 70 of three sheets forming a part of the following specification I have illustrated my invention in what I believe to be the best method to carry the same in practice and in which,

Figure 1, is a vertical central sectional view of a deep well and its metallic casing having therein my improved system of pump consisting in this case, of two sections with their impellers in position therein 80 showing a vertical section and a portion thereof in elevation showing also the pump and the deep well broken away in two places for the purpose of shortening the length of same. Fig. 2, is a cross section taken on dotted line *a—a* of Fig. 1, showing particularly the outlet channel of the auxiliary chamber, and spiral passages. Fig. 3, is a cross section taken on dotted line *b—b* of Fig. 1, showing particularly the removable 85 diffusion vanes on the casing and the waterways on the lower part of the impeller in communication therewith. Fig. 4, is a cross section taken on dotted line *c—c* of Fig. 1 showing particularly the inward projecting 90 flange of the receiving chamber and the depressions and ribs thereon. Fig. 5, is an elevation of the impeller detached from the casing showing the water-ways and rifles upon the bearing faces. Fig. 6, is a broken 95 vertical section of an enlarged portion of a bearing face of the casing showing the rifles thereon. Fig. 7, is a vertical section of a portion of the casing in which the impeller

is inclosed showing the diffusion vanes in dotted line, and the riffles on the bearing faces. Fig. 8, is a central sectional view of a portion of a deep well and one section of my system of pump in position therein showing a modification thereof. Fig. 9, is a cross section taken on dotted line *d-d* of Fig. 8 and Fig. 10 is also a cross section taken on dotted line *e-e* of Fig. 8.

10 Similar characters of reference denote like parts throughout the several views.

Referring to the drawings 1 is a lower casing, 2 an upper casing and 3 the bottom of the lower casing while the upper part 15 of this casing forms in this case the bottom of the upper casing 2, thus forming two sections of a pumping plant as they appear below the water line A. The bottom 3 and the upper part of the casing 1 are 20 removably secured in position for the purpose of adjusting or removing the impellers 4 from their respective section and which are mounted upon the shaft 5 supporting them in central position within the casings.

25 The lower end of the impellers 1 fit in a central suction aperture 6 formed through the bottom 3 and is provided with an annular depression 7 to form a shoulder 8 which rests upon the upward annular projection 9 made around the suction aperture 6 of the bottom 3 and thereby supporting the weight of the impeller and its shaft when they are at a stand still.

Near the lower portion of the impeller 35 are water-ways 10 shown in Figs. 1, 3 and 5, which are in communication with the suction aperture 6 and above the water-ways is the receiving chamber 11 formed within the upper part of the impeller immediately 40 opposite the auxiliary chamber 12 on the casing and in constant communication therewith in which leakage from the running surrounding joints between the impeller and its casing accumulate and pass under pressure into the auxiliary chamber 12 and out 45 through the channels 13 into the well 14 as fully shown in Figs. 1 and 2. The upper edge of the receiving chamber 11 is provided with an annular inwardly projecting flange 50 15 corresponding with a similar flange 16 around the auxiliary chamber 12. The faces of these flanges are provided with interspaced recesses 17 which form surrounding 55 ribs 18 shown particularly in Fig. 4 adapted to keep back the leakage from the running joints between the impeller and the casing down to a minimum degree. The inner edge 19 of flange 15 projects upwardly as shown in Fig. 1 so that when the impeller moves in an upward direction by 60 pressure against the impeller below the water-ways 10 the edge 19 will meet the inner edge 20 of flange 16 and close the inlet of the leakage which otherwise forces 65 its way into the receiving chamber 11

through the running joints at that point between the impeller and its casing and thus creating a pressure in the space between the flanges 15 and 16 greater than the pressure below the water-ways and thereby forcing 70 the impeller to move downwardly to its normal position. At the lower portion of the casing are the diffusion vanes 21 in communication with the water-ways 10 and are adapted to increase the pressure on the 75 water passing at that point into the spiral passages 22 and 23 shown in Figs. 1 and 2. These vanes are removably supported opposite the water-ways 10 by a suitable frame consisting of a lower circular flange 24 secured in place by screws 25 at the lower part of the casing and an upper ring 26 projecting above the upper edges of the water-ways 10, these features are shown in Figs. 1, 3 and in dotted line Fig. 7.

85 As it appears in Fig. 1 the pumps are supported in position within the well 14 by pipe 27 secured to the upper part of the casing of the top pump by suitable flange 28 bolted thereon and form a water passage with an 90 outlet 29 above the ground and the shaft 5 is supported in central position within the pipe just mentioned by an intermedial flange 30 projecting outwardly and secured to the pipe by means of flanges 31 and bolts 95 32 and provided with inward projecting arms 33 having a central sleeve 34 supporting in position therein a wood bushing 35 which forms the central bearing of the shaft, and the pump casings are similarly provided to 100 support the shaft in central position therein. Surrounding the shaft and secured to the upper end of the wood bushing just mentioned is a cylindrical casing 36, having 105 therein suitable packing and at its top end a loose Babbitt ring 37 to press the packing around the shaft and thereby preventing the sand or other foreign matters to settle in the bearing, as shown in Figs. 1 and 8. The bearings are lubricated by 110 means of a pipe 38 secured along the water passages 27 and the pump casing and connected to the bearing by means of extension pipe 39 and having at its top an oil cup 40 or other means of supply. These features are shown only in Fig. 1. On the bearing faces of the running joints between the impeller and the casing are the riffles 41 for the purpose as above mentioned to check 115 the leakage and force the water backward, and which are shown only in detailed Figs. 5, 6 and 7.

120 In operation the water passes from the suction aperture 6 into the water-ways at the lower end of the impeller and then through the removable diffusion vanes 21 into the spiral passages 22 and 23 of the casing and therefrom into the next impeller and as the water enters therein the pressure increases and continue so from section to 125 130

section, while the water is forced therethrough. While the water under pressure moves upwardly through the various vanes and passages a leakage occurs in the running joints between the impeller and the casing which forces its way between the flanges 15 and 16 and then into the receiving chamber 11 and out in the auxiliary chamber 12 into the well 14 through the channels 5 13 which forms the outlet, but if the pressure increases and forces the impeller to move upwardly and partly closes the passage between the inner edge 19 and 20 of the flanges 15 and 16 that will create a pressure 10 in the space between the flanges greater than the pressure against the impeller and force the same back to its normal position thus preventing the upper part of the impeller 15 to bear against the casing.

20 The modification shown in Figs. 8, 9 and 10 relate only to the described receiving chamber 11 of the impeller and the flange 16 of the casing, in which I dispense entirely with the receiving chamber, and simply 25 form instead a hollow space 42 to reduce the metal at that part of the impeller, and extend the flange 16 of the casing inwardly to form a narrow passage 43 around the shaft 5 and a larger space 44 between the 30 flange 16 and the top part of the impeller; thus constructed the leakage passing through the running joints between the impeller and the casing forces its way into the space 44 then through the narrow passage 43 into the 35 auxiliary chamber 12 and out into the well 14 through the outlet 13. In this case if the impeller under pressure move upwardly that will close the narrow passage 43 and create a pressure between the flange and the 40 upper part of the impeller greater than the upward pressure, and the result will be as previously mentioned.

Believing I have produced novel and useful improvements in that class of inventions 45 and having described the same to enable others skilled in the art to which it appertains what I claim and desire to secure by United States Letters Patent is:

1. In a centrifugal vertical pump, the 50 combination with the impeller and its casing, a discharge passage in said casing, inwardly projecting annular flanges upon said impeller and said casing communicating with said discharge passage and recesses 55 upon said flanges forming therebetween pressure chambers when said flanges come together.

2. In a centrifugal pump, the combination 60 with the impeller and its casing, an annular flange on the upper part of said impeller, projecting inwardly from the outer edge thereof, a corresponding flange on the casing, facing said impeller flange and each provided with a plurality of recesses upon 65 their outer faces adapted to form pressure

chambers therebetween when said flanges come together.

3. In a centrifugal pump, the combination with the impeller and its casing, a receiving chamber in said impeller and a discharge 70 chamber in said casing in communication with said receiving chamber, inwardly projecting annular flanges upon said impeller and said casing and recesses upon said flanges forming therebetween pressure chambers when said flanges come together. 75

4. In a centrifugal pump, the combination with the impeller and its casing, a receiving chamber at the upper end of said impeller adapted to receive leakage from the running 80 joints, a discharge chamber provided with an outlet in communication with said receiving chamber and inwardly projecting flanges on the edges of said receiving and discharge chambers having means adapted to form a 85 pressure chamber therebetween.

5. In a centrifugal pump, the combination with the impeller and its casing, a receiving chamber in the impeller, an auxiliary chamber in the casing, flanges projecting inwardly from the edge of said chambers and provided with interspaced recesses adapted 90 to form pressure chambers therebetween, and a channel in said casing chamber adapted to discharge leakage under pressure into the 95 well from said chambers.

6. A centrifugal pump comprising in combination a casing provided with a water passage, an impeller in said casing provided with a suction inlet in communication with 100 said water-passage, a chamber in said impeller above the suction inlet and adapted to receive leakage from the running joints of the impeller, an auxiliary chamber in the casing provided with an outlet adapted to 105 discharge said leakage, inwardly projecting flanges on said receiving and auxiliary chambers and interspaced recesses on said flanges therebetween.

7. A centrifugal pump comprising in combination a casing provided with a water-passage, an impeller in said casing provided with a suction inlet, a chamber in said impeller in communication with the joints between said impeller and the casing and 115 adapted to receive leakage therefrom and means above said chamber to discharge said leakage.

8. A centrifugal pump comprising, in combination, a casing provided with a water-passage, an impeller in said casing provided with a suction inlet and water-ways, a chamber on the impeller above said water-ways, inwardly projecting flange on said chamber adapted to receive leakage between 120 the joints of said impeller and the casing and an auxiliary chamber in the casing provided with an outlet adapted to discharge 125 said leakage.

9. In combination with a pump casing 130

4
provided with passages, an impeller in said casing provided with inlet suction and water ways, intermedial vanes in said casing below said water ways in communication
5 with said inlet suction and said passages and means secured in said casing for adjusting and removing said vanes.

In testimony that I claim the foregoing I have hereto set my hand this 7th day of March, 1912, in the presence of witnesses.

FERDINAND W. KROGH.
